T. SCHULZ.

WINDOW.

APPLICATION FILED JUNE 14, 1912.

1,073,638.

Patented Sept. 23, 1913.

UNITED STATES PATENT OFFICE.

THEODORE SCHULZ, OF JERSEY CITY, NEW JERSEY.

WINDOW.

1,073,638.

Specification of Letters Patent. Patented Sept. 23, 1913.

Application filed June 14, 1912. Serial No. 703,676.

To all whom it may concern:

Be it known that I, THEODORE SCHULZ, a citizen of the United States, and residing at Jersey City, in the county of Hudson and State of New Jersey, have invented certain new and useful Improvements in Windows, of which the following is a specification, such as will enable those skilled in the art to which it appertains to make and use the

same.

This invention relates to the construction of windows, and particularly to means or devices for locking the sashes in a closed position, and for preventing the rattling of the sashes and for making the window both air and water tight, or approximately so; and the object of the invention is to provide a window with improved means or devices for accomplishing the above results, and which are simple in construction and operation and convenient of manipulation, and which do not affect the general construction of the window frame to any considerable extent, and whereby the sashes may be held in different positions of adjustment.

The invention is fully disclosed in the following specification of which the accompanying drawing forms a part, in which the separate parts of my invention are designated by suitable reference characters in each of the views, and in which:

Figure 1 is an inside view of a window constructed according to my invention; Fig. 2 a partial vertical section on the line 2—2 of Fig. 1 in which the top and bottom of the window frame and parts connected therewith are shown in section, and one side of said frame with parts connected therewith, removed; Fig. 3 a transverse section on the line 3—3 of Fig. 1; Fig. 4 a sectional detail view on the line 4—4 of Fig. 2; Fig. 5 a section on the line 5—5 of Fig. 2; Fig. 6 a section on the line 6—6 of Fig. 2, and Fig. 7 a detail of the construction shown in Figs. 2 and 5.

In the drawing forming part of this specification I have shown at *a*, an ordinary window frame comprising side members *a*², a top member *a*³, and a bottom member *a*⁴, and the side members of the frame are provided with the usual inner bead strip *b* and outer bead strip *b*², and the top member *a*³ of the frame is provided with a forwardly and backwardly adjustable strip *c* which corresponds with the inner bead strip *b* and which operates in connection with the top

sash *d*, and the bottom member *a*⁴ of the frame is provided with an inwardly and outwardly adjustable strip *c*² which also corresponds with the inner bead strip *b* and operates in connection with the bottom sash *e*, and the top member *a*³ of the frame is also provided with an outer transverse strip *b*³ which corresponds with the outer bead strips *b*² at the sides of the frame.

60
65

The top sash *d* is beveled on the inner side thereof and at the top thereof, as shown at *d*², and the bottom sash *e* is similarly beveled at the bottom thereof, as shown at *e*².

The top strip *c* is provided with metal plates *c*³ and formed therein and in said strip are transverse slots *c*⁴ through which are passed screws *c*⁵ by which said strip *c* is secured to the top frame member *a*³, and by means of this construction, the strip *c* 70
75
80
85

may also be adjusted inwardly and outwardly, and this strip bears on the beveled surface *d*² of the top sash *d* and securely binds said sash against the outer strip *b*², when said sash is in its closed position. The bottom strip *c*² is also provided with plates *c*³, slots *c*⁴, and screws *c*⁵, the same as the top strip *c*, and by means of this construction said bottom strip *c*² may be adjusted inwardly and outwardly.

85
With my improvement there are no central bead strips at the sides of the top portion of the frame, but I provide central bead strips *f* which are secured to the sides of the frame in the bottom portion thereof, and 90
95
which are composed of strips of metal which are L-shaped in cross section, and in which the bottom sash *e* is vertically movable, and said bead strips *f* are pivoted centrally thereof to the sides of the frame, as shown 95
at *f*², by means of headed rivets which are passed through key-hole slots *f*³ formed in plates *f*³ countersunk in the sides of the frame, as clearly shown in Fig. 5.

The bottom frame member *a*⁴ is provided 100
at the opposite sides of the frame under the central bead strips *f* with wear plates *g* which are countersunk therein, and the side portions of the L-shaped bead strips *f* are provided with fingers *f*⁴ movable in the bottom frame member *a*⁴, as clearly shown in Fig. 6. The sides of the frame are also provided at the top of the bead strips *f* with plates *h* which are secured thereto, and the side portions of the bead strips *f* are provided with fingers *f*⁵ movable in recesses 105
110
back of the said plates, as shown in Fig. 4.

With this construction it will be seen that the bead strips *f* constitute rock bars or supports in which the bottom sash *e* is vertically movable, and the bottom sash *e* is provided at the top thereof with wear plates *i* and the inner side bead strips *b* are provided centrally thereof with casings *j* in which are pivoted lock levers *k* provided with cam heads *k*² which are adapted to bear 10 in the plates *i*, and when said levers *k* are in the position shown in Fig. 2, the top part of the bottom sash *e* is forced outwardly against the bottom part of the top sash, while the bottom part of the bottom sash is 15 forced into air tight engagement with the strip *c*² by the bottom part of the strip *f* and said sashes are locked together and cannot be moved vertically, but when the levers *k* are pulled down into the position shown in 20 dotted lines, in Fig. 2, the sashes *d* and *e* are not locked together and said sashes may be moved vertically in the usual manner.

The sashes *d* and *e* may be counterbalanced by cords and weights in the usual 25 manner so as to permit of their being easily raised and lowered, in the usual manner, and adjusted into any desired position, and said sashes may be locked in the position by the levers *k*, or said sashes may be raised 30 and lowered by hand, or may be provided with any suitable means whereby they may be raised and lowered and adjusted into any position, and said sashes may be locked in any such position by means of the levers *k*.

The normal position of the central bottom bead strips *f* is such as to permit the top sash to be freely raised and lowered, and said bead strips *f* are made rigid by 35 reason of their L-shaped formation, and by 40 adjusting the top and bottom strips *c* and *c*², the top of the top sash *d* may be securely held in its rearmost position, while the bottom of the bottom sash will be operated as hereinbefore described, and by means of 45 this construction the rattling of the sashes may be absolutely prevented, and air and water may also be approximately excluded, or prevented from passing through the window or around the sashes.

While the levers *k* may be used, as hereinbefore stated, for the purpose of locking the sashes in any position of adjustment, the principal use of said levers is to lock said sashes together and prevent their vertical movement when closed, and for this reason 55 the wear plates *i* are made short, as shown, and said levers operate in connection therewith only when the sashes are in their closed position.

The reason for providing the sashes *d* and *e* with the beveled faces *d*² and *e*² is to prevent them from sticking and to render them easy of manipulation, and it will be seen that, in the construction shown in Fig. 2, the abutting faces of the sashes *d* and *e* are 65 straight and not beveled, as is usually the case in window sash constructions, the beveled formation being unsatisfactory by reason of the liability of slightly raising the lower sash when the sashes are locked together, which condition will permit of rain and air entering at the bottom of the window, as will be readily understood.

Having fully described my invention what I claim as new and desire to secure by Letters Patent is:—

A window frame provided with the usual inner and outer side bead strips, and central side bead strips which extend from the bottom of the frame to the top of the bottom 80 sash only, and which are pivoted centrally thereof to the sides of the frame, said central bead strips consisting of bars which are L-shaped in cross section and in which the bottom sash is vertically movable, and the 85 inner bead strips being provided with means for forcing the top of the bottom sash outwardly against the bottom part of the top sash and for locking the sashes against vertical movement.

In testimony that I claim the foregoing as my invention I have signed my name in presence of the subscribing witnesses this 13th day of June, 1912.

THEODORE SCHULZ.
